CLAIM

The ornamental design for an airway device, as shown and described.

DESCRIPTION

FIG. 1 is a front view of the airway device showing our new design;

FIG. 2 is a rear elevation view thereof;

FIG. 3 is a side elevation view thereof;

FIG. 4 is a top plan view thereof;

FIG. 5 is a top perspective view thereof;

FIG. 6 is a bottom perspective view thereof; and,

FIG. 7 is a bottom plan view thereof.

The broken line showing of portions of the article is included for the purpose of illustrating structural environment and forms no part of the claimed design.

1 Claim, 2 Drawing Sheets
